(No Model.)

J. F. BALL, Jr.
CAR COUPLING.

No. 605,624.

Patented June 14, 1898.

FIG. 1.

FIG. 2.

FIG. 3.

UNITED STATES PATENT OFFICE.

JOHN F. BALL, JR., OF TURTLE CREEK, WEST VIRGINIA.

CAR-COUPING.

SPECIFICATION forming part of Letters Patent No. 605,624, dated June 14, 1898.

Application filed December 20, 1897. Serial No. 662,639. (No model.)

To all whom it may concern:

Be it known that I, JOHN F. BALL, Jr., a citizen of the United States, residing at Turtle Creek, in the county of Boone and State of 5 West Virginia, have invented a new and useful Car-Coupling, of which the following is a specification.

The invention relates to improvements in car-couplings.

10 The object of the present invention is to improve the construction of car-couplings and to provide a simple, inexpensive, and efficient one capable of coupling automatically and adapted to be readily uncoupled without necessitating a person going between cars and guiding the link by hand.

15 The invention consists in the construction and novel combination and arrangement of parts, as hereinafter fully described, illustrated in the accompanying drawings, and pointed out in the claims hereto appended.

20 In the drawings, Figure 1 is a perspective view of a car-coupling constructed in accordance with this invention and shown applied to a car. Fig. 2 is a longitudinal sectional view showing two draw-heads coupled. Fig. 3 is a detail perspective view of the link-bar.

25 Like numerals of reference designate corresponding parts in the several figures of the drawings.

30 1 designates a draw-head mounted on a car 2 in the usual manner and provided with a coupling-pin perforation 3, receiving a coupling-pin 4, which is pivoted to and carried by 35 a lever 5, disposed longitudinally of the draw-head and fulcrumed at its rear end thereon. The rear end of the lever is pivoted in a bracket or support 6 and is provided with an upwardly-extending arm 7, having a lug 8 40 and engaged by a spring 9, which bears against the lug and holds the coupling-pin in engagement with a link-bar 10. The lug 8 extends rearward from the arm 7, and the spring which is secured upon the draw-heads is 45 adapted to hold the lever normally depressed.

45 The coupling-pin 4, which is provided at its top with a bifurcated head, is pivoted to an ear of the lever 5 at a point between the ends thereof and engages a perforation 11 of the 50 link-bar 10. The front end of the lever is provided with a depending arm forming a hook 12 and adapted to engage a lug 13 of the

link-bar 10. The link-bar, which has its ends beveled, is provided at each end with a perforation 11 and a lug 13, and the latter is 55 beveled at its outer edge and is adapted when the link enters the draw-head to engage the front end of the lever and lift the same, whereby the coupling-pin is raised preparatory to automatic coupling. As soon as the 60 front end of the lever passes over the lug it falls and the coupling-pin drops into engagement with the link-bar. The inner edge of the lug forms a straight shoulder which is engaged by the hook of the lever, whereby the 65 link is doubly locked in the draw-head.

The draw-head is provided, in advance of the coupling-pin perforation, with an opening 14, disposed longitudinally of the top portion of the draw-head and extending inward 70 from the outer end thereof to receive the hook 12, which has its terminal upturned at 15 in order to be readily engaged by the beveled lug 13.

The lever is provided between its ends with 75 an upwardly-extending ear, to which is connected one end of a chain 16, and the other end thereof is attached to a shaft 17; but any other suitable uncoupling mechanism may be provided. The shaft 17 is journaled in suitable bearings of the car 2 and provided with a crank-handle.

70 The invention has the following advantages:

75 The car-coupling, which is simple and comparatively inexpensive in construction, is automatic in its operation and does not require a person to go between cars and guide the link by hand.

80 The car-coupling is adapted to be readily uncoupled, and there is no liability of the link becoming accidentally released from the draw-head, owing to the double locking action of the coupling.

85 Changes in the form, proportion, and minor details of construction may be resorted to without departing from the spirit or sacrificing any of the advantages of this invention.

85 What I claim is—

90 1. In a car-coupling, the combination of a draw-head, a lever fulcrumed at its rear end on the draw-head, a coupling-pin connected with the lever at a point between the ends of the latter, and a link provided between its

ends with a lug or projection arranged to engage and lift the lever, said link being provided at its ends beyond the lug with an opening adapted to receive the coupling-pin, substantially as described.

2. In a car-coupling, the combination of a draw-head, a lever fulcrumed at its rear end on the draw-head, a coupling-pin connected with the lever at a point between the ends thereof, and a link provided between its ends with a beveled lug arranged to lift the lever and interlocking with the front end thereof, said link being provided at its end beyond the lug, with an opening adapted to receive the coupling-pin, substantially as described.

3. In a car-coupling, the combination of a draw-head, a lever fulcrumed at its rear end on the draw-head and provided at its front end with a depending hook, a coupling-pin connected with the lever at a point between the ends thereof, and a link provided with a beveled lug adapted to raise the lever and en-

gaging the hook, said link being provided beyond the lug between the same and its end with a perforation to receive the coupling-pin, substantially as described.

4. In a car-coupling, the combination of a draw-head, a lever fulcrumed upon the same at its rear end and provided with an upwardly-extending arm having a lug, the front end of the lever being provided with a hook, a coupling-pin connected with the lever, a spring mounted on the draw-head and engaging the said lug, and a link provided with perforations and having lugs adapted to engage the said hook, substantially as and for the purpose described.

In testimony that I claim the foregoing as my own I have hereto affixed my signature in the presence of two witnesses.

JOHN F. BALL, JR.
